UNITED STATES PATENT OFFICE.

EARL HAUSTIN REYNOLDS, OF STERLING, ILLINOIS.

ENVELOP-FEEDING ATTACHMENT FOR TYPE-WRITERS.

SPECIFICATION forming part of Letters Patent No. 699,975, dated May 13, 1902.

Application filed March 31, 1900. Serial No. 10,946. (No model.)

To all whom it may concern:

Be it known that I, EARL HAUSTIN REYNOLDS, a citizen of the United States, residing at Sterling, in the county of Whiteside and State of Illinois, have invented certain new and useful Improvements in Envelop-Feeding Attachments for Type-Writers, of which the following is a specification.

My invention relates to certain new and useful improvements in envelop-feeding attachments for type-writing machines intended to be used in connection with any kind of machine of this nature to which it is adapted, with such modifications, changes, and additions as may be necessary to attach it to a particular machine.

One of the primary objects of this invention is to provide a comparatively simple and inexpensive attachment which can be connected and embodied with an ordinary type-writing machine for automatically feeding envelopes thereto and arranging same in position to receive an address without requiring any attention on the part of the operator for this purpose.

Another object of the invention is to provide mechanism and devices which can be embodied with an ordinary type-writer for feeding envelopes thereto automatically and which are set in action by the operator when shifting the carriage into position to begin a new address.

Another object of the invention is to provide for arranging a supply of blank envelopes in a convenient position with relation to the type-writing machine and from which supply the envelopes are automatically fed one by one into position for receiving the address.

Another object of the invention is to provide a carrier intermediate of the envelop-supply and the platen of the type-writing machine which adjusts the envelop in its proper position and from which the envelop is fed at the proper time to the platen.

A further object of the invention is to provide for separating the holding or pressing rollers from the platen at the proper time, so that the envelop may readily be fed into position with relation to the platen to receive the address.

My invention also has numerous other objects in view, which will be fully and care-

fully pointed out hereinafter in the detailed description, among which are to provide stop-guides whereby the envelop is properly adjusted with relation to the platen and for releasing these stop-guides, so that the envelop may be fed around the platen, for shifting the carriage and actuating the feeding devices of my improved attachment, and for accomplishing various other movements and results which will be fully explained.

In the accompanying drawings, Figure 1 is a perspective view of my improved attachment applied to a type-writing machine, so much of the machine being illustrated as is necessary to understand the application of the invention. Fig. 2 is a top plan view of the machine and attachment as illustrated in Fig. 1. Fig. 3 is a front elevation. Fig. 4 is a side elevation looking from the left of the machine, a part of the envelop-supply device being broken away. Fig. 5 is also a side elevation looking at the right of the machine. Fig. 6 is a sectional view. Fig. 7 is a detailed sectional view of the envelop-supply device and carrier, showing these parts in their proper relation to each other. Fig. 8 is a top plan view of the type-writing machine with the envelop-supply and carrier devices removed and showing the parts of my invention which are attached to the ordinary type-writing machine. Fig. 9 is a detail rear elevation of the carriage and parts connected therewith. Figs. 10 and 11 are detail views, partly in section, showing the stop-guides and the manner in which they operate. Fig. 12 is a top plan view, partly in section, showing the device for operating the roller-platen of the machine. Fig. 13 is a detailed enlarged cross-sectional view of the platen and showing the holding-rollers. Fig. 14 is a detailed view showing the manner of supporting the carrier. Fig. 15 is a detailed view of the feeding and locking dogs at the envelop-supply.

It will be understood that in the ordinary operation of addressing envelopes, the address comprising three lines of writing, the type-writing machine is operated in exactly the same manner as is customary without my improved feeding attachment connected therewith, the operator manipulating the keyboard, the line-spacing devices, and the carriage-shifting devices in the usual manner,

excepting that I provide a special shifting device, which, however, is operated in substantially the same manner as the ordinary shifting device.

- 5 Referring to the drawings, in which like numerals of reference denote corresponding parts in all of the figures, 1 designates the frame of the machine to which my attachment is applied, this machine comprising also 10 a carriage 2, traveling on the tracks 3 in the usual manner and provided with a roller-platen 4, which is mounted in the carriage in the usual manner on a shaft 5. The carriage is also provided with a lever-arm 6, by means 15 of which the platen-feeding dogs 7 and 8 are operated and the carriage is shifted. The carriage is also provided with a supplementary shifting device 9, as is usual in a machine of this character.
- 20 The envelop-supply holder 10 is mounted on a standard 11, which may be connected with the frame of the type-writing machine or otherwise located at the rear thereof. This holder is substantially in the form of a chute 25 provided with the inclined bottom 12, so that the supply of envelops will always feed down toward the open front of the holder. To maintain the supply of envelops in an upright position, I provide stop devices, which 30 comprise the arms 13, carried by the adjustable brackets 14, secured on the sides of the holder by simple screw devices, so that the arms 13 can be adjusted for envelops of different sizes.
- 35 The envelops are fed from the holder one at a time, and the feeding devices comprise the slotted holding-dog 15 and the temporary holding-dog 16, Fig. 15, these dogs being independently mounted in the following manner: The temporary holding-dog 16 operates 40 through a slot of the main holding-dog 15, and it is carried on a yoke 17, pivotally secured to the sides of the holder at 18, Figs. 4, 5, 6. This temporary holding-dog is normally out of engagement with the envelops 45 in the holder, as shown in Fig. 6, and it is caused to rise through the slot of the main holding-dog into a position behind the first envelop and against the second envelop of the supply, Fig. 7, to hold all except the first envelop, so that when the main holding-dog 15 drops the first envelop is free to fall into the carrier. A bell-crank lever 19 is pivotally supported on the standard and has one 50 arm extending downward to be engaged with the carriage, hereinafter described, so that when the carriage is shifted to begin a new address on a fresh envelop this bell-crank lever will be rocked, thereby causing its horizontal arm to engage and lift the yoke 17 and carry the temporary holding-dog up into engagement with the envelops, as hereinbefore described. The main holding-dog is carried on a rock-shaft 19', which is provided at its outer 55 end with an arm 20, having a cam-shoulder 21 thereon. The yoke 17 is provided with a lug 22, and the arm 20 is held in engagement

with this lug by means of a spring 23, so that while the spring normally holds the arm 20 down and the holding-dog in engagement with the envelops this arm is raised by the engagement of the lug 22 with the cam-shoulder 21 when the yoke 17 is elevated, as previously described, thereby releasing the main holding-dog from the envelops at the same time 75 as the temporary holding-dog is carried up to prevent the envelops behind the first one from feeding. I also provide a bar 24 at the front of the holder, which will prevent the envelops from falling out of the holder improperly during the feeding operation and cause them to drop into the carrier in the proper manner.

From the supply-holder the envelops drop into a carrier, which is supported on the carriage and travels thereon, normally holding an envelop ready to be fed into printing position. This carrier consists of a plate 25, corresponding in width substantially with the holder and provided with sides 26 and guides 27 to prevent the envelop from falling forwardly out of the carrier. On the back I provide brackets 28, Fig. 14, by means of which the plate is supported on the carriage, and in this embodiment of my invention the brackets are provided with slots 29 to receive the shaft 30, on which the holding-roller devices are supported. I also provide an arm 31 on the carrier and by means of which the carrier is rigidly secured in place on the carriage. 100

The envelop drops into the carrier and is supported at or about the middle thereof on the ends of the temporary supporting-arms 32, these arms being rigidly secured to a rock-shaft 33, journaled in bearings in the brackets 28, and their ends normally held in contact with the face of the carrier by means of a spring 34, so that when the envelop drops into the carrier it will rest upon the ends of these arms. One end of this rock-shaft 33 is 110 provided with a downturned end 35, which is adapted to be engaged by suitable devices connected with and operated by the carriage-shifting mechanism, so that whenever the carriage is shifted into position for beginning 115 a new address upon a fresh envelop the temporary supporting-arms will be withdrawn from their position in contact with the face of the carrier and the envelop which has been supported by these arms will drop into position between the roller-platen and the holding-rollers, the platen being also operated at this time to carry the envelop around into position for receiving the first line of the address. 120

At the back of the carriage I arrange a lever 36, which is pivotally mounted on a bracket 40, secured on the shaft 30 of the carriage and at or about its middle. One end of this lever is provided with a hooked arm 37, which engages and interlocks with a vertically-arranged arm 38 on one end of the shaft 39, which usually carries the scale located adjacent to and beneath the roller-platen. This 125

arm 38 is located just in advance of the down-turned end 35 of the rock-shaft 33 on the back of the carrier, so that when this lever is turned on its pivot the hooked end thereof will engage 5 and pull back the arm 38, thereby rocking the scale-shaft 39 and at the same time also rocking the supporting-arms shaft 33. In order that the holding-rollers may be carried away from the roller-platen at the 10 time that the envelop drops down into engagement therewith, so as to facilitate its arrangement relative to the platen in position for printing, I provide lugs 41 on the scale-shaft 39, which are arranged to engage the 15 studs 42, carried by the arms 43, which are mounted on the shaft 30 and carry the holding-rollers 44 on their lower end. It will therefore be observed that when the lever operates to pull back the arm 38, as hereinbefore described, the shaft 39 will rock and cause the lugs 41 to engage the studs 42, Fig. 6, and force the holding-rollers 44 away from the platen-roller a slight distance, which is sufficient to permit the envelop to fall readily 20 into position between the holding-rollers and the platen-roller. The particular construction of the holding-rollers is unimportant so far as my invention is concerned, and it may consist of a single continuous roller 25 or of several rollers mounted on a shaft supported by two arms 43 at the ends of the carriage. On the back of the carriage I also mount rigidly the arm 45, which travels with the carriage and projects outward and in such 30 a position that it will engage and operate the downwardly-extending arm of the bell-crank lever 19, which operates the dogs of the envelop-holder. When the carriage is shifted, this arm 45 will operate the bell-crank and 35 cause the first envelop of the supply to drop down into the carrier and take the place of the envelop which has been fed from the carrier into position for printing. These operations are automatic and performed simultaneously, so that the shifting of the carriage not only feeds an envelop into position for printing, but also brings an envelop from the supply into the carrier ready to be fed into position for printing at the next operation, 45 and, as will be explained farther on, the envelop which has just been printed is also ejected by the shifting movement of the carriage.

I will now proceed to describe the devices 50 employed for shifting the carriage, ejecting the addressed envelop, and operating the lever 36 simultaneously and the manner in which they are actuated and operated. As hereinbefore described, the carriage is provided with the usual shifting-lever 6; but when my improved attachment is embodied with the machine this lever is employed for line-spacing—that is to say, for turning the roller-platen at the proper time to begin a new line of the address—and not for shifting the carriage, another device being employed for this purpose.

I provide a pulley 46, which is supported on an arm 47, fastened to the frame of the machine and extending outwardly from the 70 right-hand side thereof, as clearly shown in Fig. 1. I also provide another pulley 48, which is supported on a bracket 49, rigidly secured to the right-hand side of the carriage, this bracket also supporting a swing-arm 50, provided with an opening 51 in its end. The shaft 5, which carries the roller-platen, projects through the frame and carries on one end the ratchet-wheel 52, which is provided with an elongated hub 53, on 80 which a pulley 54 is loosely mounted, this pulley being provided with a pawl 55, which is normally held in engagement with the ratchet-wheel 52 by means of a spring 56, Fig. 12. A stop-plate 57 is secured on the 85 side of the pulley 54, diametrically opposite the pawl 55, and it projects beyond the periphery of the pulley, so as to engage the stop-bar 58, supported on the frame of the machine. A pull-cord 59, provided with a 90 handpiece 60, passes around the pulley 46, the pulley 48, and the pulley 54, its end being secured to a bar 61 on the latter pulley or in some other convenient and suitable manner. When the handpiece 60 is pulled, the cord 95 will operate to revolve the pulley 54, the pawl 55 engaging the teeth of the ratchet-wheel 52 and causing said ratchet-wheel and the shaft, Fig. 5, to which it is rigidly secured, and therefore the roller-platen, to turn 100 with the pulley 54 until the stop-plate 57 has engaged the stop-bar 58, which limits the movements of these parts. Upon releasing the handpiece 60 the pulley 54 is returned to its original position, the pawl 55 sliding 105 freely backward over the teeth of the ratchet-wheel under the influence of a spiral spring 62, located in a convenient position between the pulley 54 and the frame of the machine, one end of said spring being connected with 110 the pulley near its periphery and the other end being fastened to the carriage of the machine. It will thus be seen that whenever the handpiece 60 is pulled to shift the carriage into its initial position this same operation will accomplish, in addition to the shifting of the carriage, the ejection of the envelop which has been addressed from the carriage and the arrangement at the same time of a fresh envelop in position for printing. 115 All these operations are accomplished simultaneously, and these several parts are set in action, controlled, and operated entirely by the pull-cord without requiring any special attention on the part of the operator, without 120 losing time in taking the printed envelop from the machine and arranging a fresh envelop in position for printing. All of these operations are performed during the shifting of the carriage, and the parts are set in action by the one movement, which corresponds to the usual movement the operator makes to shift the carriage.

To accomplish the swinging of the lever 36,

I provide a pivoted footpiece 63 on one end thereof, which is provided with a heel 64, adapted to be swung into engagement with the teeth of a vertically-arranged rack-bar 65, 5 supported on the frame of the machine at the back thereof. The pivoted end of this foot-piece is provided with a projection 66 and connected with the swinging arm 50 by means of a cord 67, Figs. 2 and 7. The footpiece 63 10 is normally held out of engagement with the rack-bar 65 by means of a spring 68; but when the carriage has proceeded to the left in the printing operation and the handpiece 60 is pulled to shift the carriage to its initial position and set in action the other devices hereinbefore mentioned the initial tension on the pull-cord 59 will be exerted primarily upon the swinging arm 50, which is normally held by the spring 68 at an angle to the line of the 15 pulleys 46 and 48, Fig. 2, and this arm is swung around into a position substantially parallel with the line of tension on the pull-cord, thereby drawing upon the cord 67 and swinging the footpiece 63 on its pivot into engagement with rack-bar 65, Fig. 8. This movement is accomplished very quickly by the initial tension exerted on the pull-cord and before the roller-platen begins to revolve; but as the tension on the pull-cord increases and 20 the roller-platen is revolved and the carriage shifted the footpiece 63 acts as a fulcrum for the lever 36, its heel 64 engaging one of the teeth of the rack-bar, so as to retard its forward movement and operate to swing the lever 36 on its pivot. When the lever 36 is thus 25 swung on its pivot, the various devices before described are operated for feeding an envelop from the carrier into position for printing and feeding another envelop from the supply to 30 the carrier. As the carriage is shifted to its initial position the footpiece 63 slides over the rack-bar 65 and beyond the same and is returned to its initial position, Fig. 2, by the spring 68, this spring in this operation also 35 drawing the cord 67 taut and the swinging arm 50 into its angular position.

The envelop is automatically fed from the carrier into position for printing, and in order that this printing may be done in a uniform manner on all the envelops I provide 40 stop-guides 70, which are located in front of the roller-platen and have forwardly extending ends 71, against which the envelop strikes when it is fed around initially in position for 45 printing. These stop-guides are rigidly secured on a rock-shaft 72, journaled in bearings in the frame of the carriage, and the rock-shaft and stop-guides are automatically operated whenever the roller-platen is revolved 50 to space a new line. The arm 73 is rigidly secured to the lever 6, Figs. 10 and 11, and provided with a bifurcated end 74, which receives a projection 75, rigidly secured on the rock-shaft 72. The construction and arrangement of these parts is such that the stop-guides 55 70 are initially arranged in a position indicated in Fig. 10, so that when the envelop

is fed around the roller-platen in position for printing it will engage and be stopped by the ends 71 of the stop-guides, which also act to 70 register the envelop in its proper position in the machine. Then the lever 6 is operated to revolve the roller-platen for a new line of printing, and the stop-guides are swung back from their position in engagement with the 75 envelop, as shown in Fig. 10, into the position shown in Fig. 11, thereby permitting the envelop to feed upward a sufficient distance for a new line of printing, and when the lever 6 is permitted to return to its normal position, 80 as shown in Fig. 10, the stop-guides will rest against the face of the envelop without impeding or interfering with it in any way, as shown in broken lines in Fig. 11.

The lever 6 is provided with a pivoted pawl 85 76, which engages a ratchet-wheel 77, rigidly secured on the platen-shaft 5, whereby the line-spacing movement of the platen is accomplished, this being a familiar construction.

In order to facilitate the ejection of the 90 printed envelop and the arrangement of a fresh envelop in position for printing, I provide a ratchet-wheel 80 on the extended end of the platen-shaft 5 and a pivoted pawl 81 on the end of the lever 36, Fig. 8, this pawl 95 81 being at all times in engagement with the ratchet-wheel 80, so that when the lever 36 is swung on its pivot the pawl will operate to turn the ratchet-wheel and platen-shaft 5, and thereby assist the device on the other end of this shaft in accomplishing the ejection of the new envelop in position for printing.

This being the general construction of my invention, as shown in the embodiment thereof 105 illustrated in the accompanying drawings, the operation, which has been more or less described in connection with the foregoing detailed description, may be briefly referred to again, as follows: The different mechanisms and devices operate simultaneously and are set in action by the single movement of the operator to shift the carriage, and therefore it may be said that by shifting the carriage all the other movements and operations 110 of the machine are accomplished, with the single exception of withdrawing the stop-guides from engagement with the envelop. Each envelop passes through a certain cycle 115 of operations during its travel from the supply to the platen, these operations consisting, first, in being fed singly to the carrier; second, being fed from the carrier to the platen; third, being ejected from the carriage, and the operations of the parts are so timed with 120 relation to each other and connected that a continuous stream of envelops is always traveling through the different mechanisms and devices of the attachment and machine. Assuming that the machine is in position for 125 operation, one envelop being arranged in position for printing and against the stop-guides and another envelop being supported on the arms 32 in the carrier, the first operation is 130

to print the first line upon the envelop, after which the lever 6 is operated to turn the platen, withdrawing the stop-guides to permit the envelop to be fed for receiving the 5 second line of printing. Any number of lines may be printed on the envelop, this operation being performed in exactly the same manner as upon any machine without my attachment, and the various stop devices which are usually 10 employed for limiting the length of the lines of printing may be used upon a machine provided with my attachment in precisely the same manner as has heretofore been customary. When the printing has been completed, 15 the carriage has traveled to the left until the footpiece 63 is opposite the rack 65, and the operator pulls sharply and quickly upon the pull-cord 59. This single movement of the operator shifts the carriage to its initial 20 position at the right of the machine and sets in action the following mechanisms and devices, to wit: The lever 36 is swung on its pivot, and the hooked arm 37 draws backward the arm 38, so as to throw the supporting- 25 arms 32 forward and permit the envelop which has been supported thereby to drop into position between the roller-platen and the holding-rollers, which have been thrown slightly away from the roller-platen by the same operation 30 of the arm 38, so as to facilitate the entrance of the fresh envelop into position between the platen and the holding-rollers. At the same time the platen is revolved to eject the printed envelop and feed the fresh 35 envelop around into engagement with the stop-guides and in position for receiving the first line of the printing. As the carriage is shifted to its initial position the arm 45, carried thereby, strikes the bell-crank lever 19, 40 which causes the temporary holding-dog 16 to rise into engagement with the second envelop in the supply, as shown in Fig. 7, while the main holding-dog 15 drops down out of engagement with the first envelop in the supply, 45 thereby permitting said first envelop to drop down upon the supporting-arms 32 in the carrier. These operations having been all accomplished by the single movement of the operator for shifting the carriage, which 50 corresponds to the usual movement of the operator for this purpose, as before observed, it is to be noted that the feeding operations for the envelop require no attention whatever on the part of the operator, and for this reason 55 the machine can be manipulated in the usual way without necessitating the exercise of any peculiar or special skill, by reason of the fact that it has my improved feeding attachment embodied therewith.

60 The automatic feeding of the envelop makes it possible to operate the type-writing machine very rapidly, and therefore the operator is enabled to address a far greater number of envelops than has heretofore been possible, be- 65 cause all the time that has usually been required in arranging the envelop in position for printing is saved by my automatic feed-

ing attachment. Without my attachment the operator must necessarily shift the carriage, remove the printed envelop, place a fresh envelop in position between the platen and the holding-roller, and revolve the platen until the envelop is arranged in position for printing, it being also frequently necessary to adjust the envelop, so that the printing will be evenly and to some extent uniformly done. All of these 70 separate and independent operations are unnecessary when my improved attachment is applied to the type-writing machine. All the envelops are fed and arranged in position 80 for printing in exactly the same manner and precisely the same position, so that the lines of printing are necessarily horizontal and uniformly disposed, as far as may be possible, on the envelop, which greatly improves the 85 general character of the work and presents a decidedly better effect than if the addresses are located in various positions on the envelops. As the carrier travels with the carriage, it is always in position to receive the 90 envelop when it drops from the supply, and this carrier is of a width corresponding substantially to the length of the envelop, so that the envelop when falling upon the arms 95 32 will be squared in position to be properly fed to the platen.

My improved attachment can be applied, with such modifications, changes, and additions as may be necessary, to almost, if not quite, all of the different kinds of type-writing 100 machines now on the market, and I believe that the character of my invention is such that it can be adapted and applied to any type-writing machine. It is also possible that the invention can be adapted for doing other work besides addressing envelops, and although this is the special object and embodiment of the invention I do not wish to be understood as limiting myself specifically thereto. I have not shown all the parts of 110 an ordinary type-writing machine in the drawings, as it is not considered necessary; but it is believed that sufficient of the machine has been illustrated and described to enable those skilled in the art to fully understand 115 the construction and operation and adaptability of my invention.

I have found from a practical use of machines embodying my invention that the best results will be attained by giving to the 120 platen three successive movements in restoring it to normal position—to wit, first, a partial rotation, next an endwise movement without rotation, and, finally, further rotation in the same direction. The first movement 125 serves to move the addressed envelop around, so that when a fresh envelop starts under the platen there will be no danger of it overlapping the edge of the printed envelop which would result in its running out of the machine along with the printed envelop when the latter is ejected. The second movement 130 restores the platen, with the carriage, to normal position at the commencement of print-

ing. The third movement serves to eject the printed envelop and run a fresh envelop into position on the platen for printing. These movements will be readily understood by an inspection of Fig. 1, which shows the carriage at the end of its travel to the left after the envelop on the platen has been printed, at which time a fresh envelop has dropped down into the carriage ready to be dropped down between the platen and feed-roller. The first movement above referred to will therefore raise the envelop on the platen a distance of about a half-inch, as shown by the dotted lines, and before the envelop in the carriage drops down, although this action follows in quick succession. The platen is next drawn fully to the right to its initial position, carrying the addressed envelop in the position shown by dotted lines and the fresh envelop down at the bottom of the carriage, with its lower edge between the platen and the feed-roller. As soon as the stop 57 passes the end of the bar 58 the final rotation of the platen takes place, which serves to eject the addressed envelop and feed into proper position the fresh envelop ready for printing, at the same time dropping another envelop from the holder into the carrier.

I have found in practice that where the tension on the platen, which yieldingly resists the rotation thereof, is weaker than the tension of the carriage-actuating spring all three of these movements of the platen will be imparted by the cord alone without the necessity for the employment of the ratchet 80 and pawl 81; but when the reversed conditions are true—that is, the platen tension is the stronger—then the first movement—to wit, the partial rotation of the platen—will be produced simultaneously with and during the early part of its endwise movement, and the pawl and ratchet 80 and 81 must be relied upon to produce this result, the endwise and final movements being produced by the pull on the cord alone. It is therefore apparent that while under certain conditions, which are generally controllable, the pawl and ratchet may be dispensed with, their presence under any circumstance is not objectionable, and under the circumstances above named, which I have encountered in some type-writers, is essential. The broad idea of my invention, however, is to give to the platen these three successive movements as the result of a single continuous pull on the cord, and I therefore do not desire to limit myself to any particular mechanism by which these movements are accomplished.

I am aware, and it will also be obvious to those who are skilled in this general line of machines that a great many changes, modifications, and alterations may be made in the construction of the various details of my improved attachment without materially departing from the invention, and I therefore reserve the right and privilege of making all

such changes as fairly fall within the spirit and scope of the invention.

Having thus fully described my invention, what I claim, and desire to secure by Letters Patent, is—

1. In an envelop-feeding attachment for type-writing machines, the combination with the carriage of the machine, of devices adapted to be operated when the carriage is shifted for ejecting an envelop therefrom, substantially as described.
2. In an envelop-feeding attachment for type-writing machines, the combination with the carriage of the machine, of means for shifting the carriage to its initial position, and devices connected with and operated by said shifting means for ejecting an envelop from the carriage, substantially as described.
3. In an envelop-feeding attachment for type-writing machines, the combination with the carriage of the machine, of devices adapted to be operated by the shifting movement of the carriage to feed an envelop to the machine, substantially as described.
4. In an envelop-feeding attachment for type-writing machines, the combination with the carriage of the machine, comprising a platen-roller and a holding-roller, of devices adapted to be operated when the carriage is shifted for separating the holding-roller from the platen-roller, substantially as described.
5. In an envelop-feeding attachment for type-writing machines, the combination with the carriage of the machine, comprising a platen-roller and a holding-roller, of means for shifting the carriage and devices connected with and adapted to be operated by said shifting means for separating the holding-roller from the platen-roller, substantially as described.
6. In an envelop-feeding attachment for type-writing machines, the combination of devices for ejecting an envelop from the machine and devices simultaneously operating to feed a fresh envelop into position for printing, substantially as described.
7. In an envelop-feeding attachment for type-writing machines, the combination with the carriage of the machine, of a carrier, a supply-holder and means for feeding the envelops separately from the holder to the carrier, substantially as described.
8. In an envelop-feeding attachment for type-writing machines, the combination with the carriage of the machine and an envelop-supply holder of a carrier located below the holder and intermediate of the holder and the carriage, substantially as described.
9. In an envelop-feeding attachment for type-writing machines, the combination with the carriage of the machine, and a holder for a supply of envelops, of a carrier located intermediate of the carriage and holder and traveling with the carriage, substantially as described.
10. In an envelop-feeding attachment for

type-writing machines, the combination with the carriage of the machine, of a holder located behind and above the carriage, and a carrier arranged between the holder and carriage and adapted to receive the envelopes from the holder and feed them singly to the machine, substantially as described.

11. In an envelop-feeding attachment for type-writing machines, the combination with the carriage of the machine, of a holder carrying a supply of envelopes, a carrier arranged between the holder and the carriage of the machine, and devices for feeding the first envelop from the supply to the carrier, substantially as described.

12. In an envelop-feeding attachment for type-writing machines, the combination with the carriage of the machine, an envelop-supply holder and a carrier located between the holder and the carriage, of devices for feeding an envelop from the supply to the carrier and devices for feeding the envelop from the carrier to the carriage, substantially as described.

13. In an envelop-feeding attachment for type-writing machines, the combination with the carriage of the machine, an envelop-supply holder and a carrier arranged between the carriage and the holder, of devices for feeding an envelop from the holder to the carrier, devices for ejecting an envelop from the carriage, and devices for feeding an envelop from the carrier into position for printing, substantially as described.

14. In an envelop-feeding attachment for type-writing machines, the combination with the carriage of the machine, an envelop-supply holder and a carrier arranged between the carriage and holder, of devices for feeding an envelop from the holder to the carrier, from the carrier to the carriage and finally ejecting the envelop from the carriage, all of said devices being operated simultaneously when the carriage is shifted, substantially as described.

15. In an envelop-feeding attachment for type-writing machines, the combination with the carriage of the machine, a holder for a supply of envelopes and a carrier traveling with the carriage of means for shifting the carriage, and devices for feeding an envelop from the holder to the carrier, devices for feeding an envelop from the carrier into position for printing and at the same time ejecting the previously-printed envelop, said devices being set in action when the carriage is shifted, substantially as described.

16. The combination with a type-writer, of an envelop-feeding attachment comprising a holder for a supply of envelopes, and main and temporary holding-dogs operating to release the first envelop in the pile and allow the same to drop freely from the holder, substantially as described.

17. In an envelop-feeding attachment for type-writing machines, a holder for a supply of envelopes, a main holding-dog normally en-

gaging the first envelop in the supply to keep the envelopes from falling out of the holder and a temporary holding-dog, and devices intermediate of the carriage of the machine and said dogs for operating the same whenever the carriage is shifted, substantially as described.

18. In an envelop-feeding attachment for type-writing machines, a holder for a supply of envelopes, a main holding-dog and a temporary holding-dog operating on said envelop-supply, devices supporting said dogs, a bell-crank lever adapted to actuate said devices to raise the temporary holding-dog into contact with the envelop-supply and depress the main holding-dog, and a device carried by the carriage for actuating the bell-crank lever, substantially as described.

19. The combination with a type-writing machine, of a carriage, a feeding attachment comprising the combination with a carrier traveling with the carriage, of arms adapted to support an envelop temporarily in the carrier and adapted when withdrawn, to permit the envelop to drop through the carrier, substantially as described.

20. In an envelop-feeding attachment for type-writing machines, the combination with the carrier supported on and traveling with the carriage of the machine, of supporting-arms adapted to support an envelop in the carrier and means for automatically operating said supporting-arms whenever the carriage of the machine is shifted, substantially as described.

21. In an envelop-feeding attachment for type-writing machines, the combination with a carrier, of pivoted arms normally arresting the movement of an envelop through the carrier and adapted to be operated to release the envelop whenever the carriage is shifted, substantially as described.

22. In an envelop-feeding attachment for type-writing machines, the combination with shifting means, of a carrier, devices for temporarily arresting the movement of an envelop through the carrier and connections between the shifting means and said arresting devices for operating the latter to release the envelop, substantially as described.

23. In an envelop-feeding attachment for type-writing machines, the combination with a platen-roller and means for revolving the same to space lines of printing, of devices normally arranged in position for limiting the feeding of the envelop and means connected with the devices for revolving the platen-roller adapted to throw the stop-guide devices out of the way of the feeding of the envelop, substantially as described.

24. In an envelop-feeding attachment for type-writing machines, the combination with a roller-platen, of a rock-shaft located in front of the platen, stop-guides rigidly mounted on said rock-shaft and provided with forwardly-turned upper ends adapted to limit the initial feeding of the envelop around the platen

in position for printing, a lever device for revolving the roller-platen for line-spacing, and an arm carried by said lever device and adapted to rock the stop-guide shaft so as to release the stop-guides from engagement with the envelop when the latter is fed through the machine to receive a second line of printing, substantially as described.

25. The combination with a type-writing machine, of a feeding attachment comprising a holder for a supply of envelopes, a main holding-dog normally in engagement with the envelopes, and a temporary holding-dog to be engaged with the envelopes behind the first 15 envelope to hold them in place while the first envelop is being fed from the holder, substantially as described.

26. In an envelop-feeding attachment for type-writing machines, the combination with 20 a carriage, of means for shifting the carriage, a platen-roller and a holding-roller carried by the carriage and devices connected with the shifting means for simultaneously ejecting the addressed envelop from the machine 25 and arranging a fresh envelop in position for printing, substantially as described.

27. In an envelop-feeding attachment for type-writing machines, the combination with a carriage, of shifting means connected with 30 the carriage a platen-roller and a holding-roller carried by the carriage and devices adapted to be operated by the shifting means for drawing the holding-roller away from the platen-roller and revolving the platen-roller

35 to eject the addressed envelop and arrange a fresh envelop in position for printing, substantially as described.

28. In an envelop-feeding attachment for type-writing machines, the combination with 40 a carriage, of a platen-shaft mounted thereon and carrying the platen-roller, a pulley on said platen-shaft, a pull-cord for shifting the carriage and trained around the pulley on the platen-shaft to revolve said shaft when the

45 carriage is shifted and means for limiting this rotation of the platen-shaft, substantially as described.

29. In an envelop-feeding attachment for type-writing machines, the combination with 50 a carriage, of a platen-shaft carrying a roller-platen, a ratchet-wheel rigidly mounted on said shaft and provided with an elongated hub, a pulley loosely mounted on said hub and carrying a pawl arranged to engage the

55 teeth of the ratchet-wheel and a pulley-cord device for shifting the carriage and connected with said pulley to revolve the platen at the same time that the carriage is shifted, substantially as described.

60 30. In an envelop-feeding attachment for type-writing machines, the combination with a carriage, of a platen-shaft mounted thereon and provided with a roller-platen, a ratchet-wheel rigidly mounted on said shaft and having an elongated hub, a pulley loosely mounted on said hub and provided with a pawl en-

gaging the teeth of the ratchet-wheel, a pull-cord for shifting the carriage and operating over the pulley to revolve the platen as the carriage is shifted, a stop-plate carried by the 70 pulley, a rigid stop-bar adapted to be engaged by the stop-plate and a spiral spring for returning the pulley to its original position after the carriage has been shifted, substantially as described.

75 31. In an envelop-feeding attachment for type-writing machines, the combination with a roller-platen and a holding-roller, of a pull-cord and devices adapted to be operated by the pull-cord for withdrawing the holding-roller away from the platen-roller and revolving the platen-roller, substantially as described.

32. In an envelop-feeding attachment for type-writing machines, the combination with 80 a roller-platen and a holding-roller, of a pull-cord shifting device and connections intermediate thereof and the roller-platen and holding-roller adapted to be operated when the cord is pulled to draw the holding-roller 90 away from the platen-roller and revolve the platen-roller, substantially as described.

33. In an envelop-feeding attachment for type-writing machines, the combination with 95 a platen-roller, of a holding-roller, a lever, connections between said lever and the holding-roller, a pull-cord adapted to shift the lever on its pivot to draw the holding-roller away from the platen-roller, substantially as described.

100 34. In an envelop-feeding attachment for type-writing machines, the combination with carriage carrying the platen-roller and a holding-roller, of a lever pivotally mounted on the carriage and connected at one end with, and adapted to draw the holding-roller away from the platen-roller and a pull-cord device adapted to swing said lever on its pivot at the same time as it shifts the carriage, substantially as described.

110 35. In an envelop-feeding attachment for type-writing machines, the combination with a carriage carrying a platen-roller and holding-roller, of a lever pivotally mounted on the carriage and having one end connected with 115 the holding-roller, a swinging arm on the carriage, a cord connected with said swinging arm and the lever and means for pulling on said cord to shift the lever on its pivot, substantially as described.

120 36. In an envelop-feeding attachment for type-writing machines, the combination with the carriage carrying a platen-roller and a holding-roller, of a lever pivotally mounted on the carriage, a rack-bar, a footpiece pivotally mounted on one end of said lever, a pivoted arm on the carriage, a cord connected to said pivoted arm and the footpiece and means for swinging the arm to throw the foot-piece into engagement with the rack-bar and swing the lever on its pivot, substantially as 125 described.

37. In an envelop-feeding attachment for type-writing machines, the combination with a carriage carrying a platen-roller and a holding-roller, of a lever pivotally mounted on the carriage, a footpiece pivoted to one end of the lever, a rack-bar, a swinging arm on the carriage, a cord connecting said swinging arm with the footpiece, and a pull-cord adapted to be operated to shift the carriage and at the same time cause the footpiece to engage the rack-bar and the lever to swing on its pivot to carry the holding-roller away from the platen-roller and partially revolve the platen-roller, substantially as described. 25
38. In an envelop-feeding attachment for type-writing machines, the combination with a carriage carrying a platen-roller and a holding-roller, of a carrier supported on the carriage, temporary supporting-arms mounted on the carrier, a lever pivoted on the carriage and a pull-cord for shifting the carriage, partially revolving the platen-roller, swinging the lever on its pivot, drawing the holding-roller away from the platen-roller and throw- 30
- ing the supporting-arms away from the carrier, substantially as described. 35
39. The combination with a type-writing machine, of a feeding attachment comprising a holder for a supply of envelopes, a main holding-dog provided with a slot and normally retaining the envelopes in the holder, and a temporary holding-dog operating through the slot of the main holding-dog and adapted to hold all the envelopes in the holder except the first envelop, while the main holding-dog is depressed to permit the first envelop to be fed from the holder, substantially as described. 40
40. The combination with a type-writing machine, of a carriage; an envelop-feeding attachment comprising the combination with a carrier traveling with the carriage, of supporting devices for temporarily arresting the movement of an envelop through the carrier, substantially as described. 45
